United States Patent Office

Des. 188,761
Patented Sept. 6, 1960

188,761

BRASSIERE

Raymond C. Cole, 29 Mary St., Dover, Del.

Filed May 19, 1959, Ser. No. 55,968

Term of patent 14 years

(Cl. D20—4)

FIG.1.

FIG.2.

I claim:

The ornamental design for a brassiere, substantially as shown.
